UNITED STATES PATENT OFFICE.

JOHN J. REKAR, OF LOS ANGELES, CALIFORNIA.

ELECTRIC LAMP.

Application filed February 12, 1923. Serial No. 618,500.

To all whom it may concern:

Be it known that I, JOHN J. REKAR, a citizen of the United States, residing at the city of Los Angeles, county of Los Angeles, State of California, have invented new and useful Improvements in Electric Lamps, of which the following is a specification.

My invention is an improvement on the lamp described in United States Letters Patent No. 1,397,453 issued to me November 15, 1921.

In the manufacture and use of that lamp it developed that the cost of manufacture was somewhat costly and that the lamp was not as perfectly ventilated as was desirable as sometimes currents of cold air would pass through openings 36 would strike the light bulb and cause it to break at such point and the lower part would fall upon and injure a person being treated. It is the object of my invention to produce a lamp in which added efficiency is produced, the cost of manufacture reduced and the danger of the light bulb being broken by cold air diminished.

In the drawings forming a part of this application Figure 1 is a central vertical section of the light bulb housing, with a bulb therein and the socket partly in section. Figures 2 and 3 are side elevations of the parts which make up the housing. Figure 4 is a side elevation of a lamp stand, partly in section supporting a casing. Figure 5 is a detail showing how two lamps may be mounted on a single standard.

Referring to the drawings 6 is a bell-shaped dome in the top of which a socket 7 is mounted. Electrical insulated wires 8 lead into and are connected to the socket in the usual manner. To the bottom of the dome is secured a parabolic skirt or reflector 9. The dome and reflector are preferably integral, being spun from sheet metal. Near the center of the dome and near the top of the reflector are vent ports 10 through which the air heated by the bulb passes. Secured to the bottom portion of the dome is a canopy 11 which surrounds reflector 9 and is spaced therefrom. This canopy is also preferably bell-shaped and those portions of its walls which project below the reflector have their inner surfaces formed into a satin finish reflector.

In the upper portion of the walls of re-

flector 9 is a row of ports 12 which permit the air between the reflector and canopy as it becomes heated to pass up into and out of the dome through the ports therein.

In Figure 4 I show the lamp standard as composed of the usual base 13 and a hollow post 14. At the top of post 14 is a pulley 15 over which a cord 16 passes. One end of the cord is attached to weight 17 which is movable in post 14 and the other end of the cord is attached to sleeve 18 slidably mounted on post 14. Sleeve 18 has a clamping lever 19 to secure it to post 14 at any desired point. Secured to and extending from sleeve 18 is a hollow arm 20 in which is mounted a sliding member 21 that is removably secured in a socket 22, which socket is secured, preferably to the canopy. A set screw 23 holds member 21 in socket 22 and a set screw 24 holds member 21 in arm 20 in its adjusted position. When the housing is separated from member 21 socket 22 may be used as a handle. Where two lamps are desired for a single standard I mount upon the outer end of arm 20 a cross bar 25 and a sliding bar 26 and pass through the ends of these bars longitudinal bars 27 on the ends of which are secured lamps as shown in Figure 5 which are secured by having the ends of the bars passed into the sockets on the housings as in Figure 1.

By this construction it will be observed that a simpler and cheaper construction is provided and that the air which lies between the canopy and reflector becomes heated and passes through the ports in the top of the reflector and on up through the dome thereby preventing cold air from striking the light bulb.

Having described my invention I claim:

1. In an electric lamp the combination of a parabolic reflector having ports in the upper part thereof; a bell-shaped dome secured to the top of said reflector having ports therein; a bulb socket mounted in said dome; and a canopy secured to the bottom of said dome, said canopy surrounding said reflector and being spaced from the bottom of the reflector and projecting below the same, said canopy having the inner surface of the walls thereof which project below the reflector adapted to reflect rays from a bulb in the socket, whereby cur-

rents of heated air pass out of the dome and prevent cold air from striking the light bulb.

2. In an electric lamp the combination of 5 a dome having a skirt, said skirt flaring outwardly at the bottom and having its inner surface adapted to reflect the light; a canopy secured to said dome above the skirt and spaced therefrom and projecting 10 below said skirt, the inner walls of said canopy being adapted to reflect light and means to mount said canopy adapted to hold the same in an elevated position.

3. The combination of a vented dome and

skirt, the inner walls of said skirt being 15 adapted to reflect light said skirt flaring outwardly at the bottom; a socket secured in said dome, a canopy secured to said dome and surrounding and projecting below said skirt and spaced from the bottom of the 20 skirt, the inner surface of said canopy being adapted to reflect light with a standard having an arm revoluble thereon; and means to secure said dome upon said arm.

In witness that I claim the foregoing I 25 have hereunto subscribed my name this 6th day of February, 1923.

JOHN J. REKAR.
